MOUNTING FOR WATCHES

Howard Cane and Daniel M. Knowles,
New York, N. Y.

Application April 20, 1950, Serial No. 157,052

7 Claims. (Cl. 58—88)

1

This invention relates to mountings for watches and more particularly to an ornamental holder in which a watch may be mounted so as to be securely retained therein.

According to the present invention, a mounting for a watch is provided which may be a natural semi-precious or precious stone or may be synthetic as will be evident. Mounting of a watch in such material has been found to be difficult and to require complex mounting means. According to the instant invention, however, we have provided means for mounting such a watch to the material without necessitating any change in the watch itself, as by the addition of mounting means thereto. On the contrary, we employ the conventional snap projections formed on the watch case as an engagement device, a groove being formed in the mounting material to receive and engage said snap projections. As a consequence, it has been found that the watch becomes so firmly and positively mounted as to insure against accidental loss, notwithstanding the fact that the watch case is not treated in any way to prepare it for such mounting. The mounting material itself is considered to be most decorative and a metal brace or band is also provided which embraces the mounting material and permits the ensemble to be suspended as from articles of apparel.

The invention will be further understood from the following description and drawings in which:

Fig. 1 is a front elevational view of a watch mounted pursuant to the present invention.

Fig. 2 is a cross-sectional view substantially along the lines 2—2 of Fig. 1.

Fig. 3 is a cross-sectional view substantially along the lines 3—3 of Fig. 1.

Fig. 4 is an elevational view illustrating the initial application of the watch to the mounting member prior to engagement thereof.

The mounting member 10 may comprise a natural semi-precious or synthetic stone or the like which may assume or be ground to any desired external configuration. It is then bored transversely so as to be provided with a central opening formed from two interconnected openings, i. e. a smaller opening 11 and a larger, circular opening 12. The larger, circular opening 12 is formed with a groove 13 throughout its peripheral or defining wall 14. The openings 11 and 12 merge into each other as illustrated so that the circular continuity of opening 12 is interrupted at its top as is the groove 13. This provides an entrance for an engaging member on the watch case, as will be hereinafter described.

2

Watch cases generally comprise a base or body member 15 which houses the watch-works including a winding crown and stem, and a frame 16 which fits over the body member and frames a lens against the dial as will be well understood. Engagement between the frame and the case body member is conventionally effected by means of complementary snap projections, the frame snap projection 17 engaging a complementary body member snap projection 18. Two pairs of such snap projections are generally provided, being oppositely disposed on the body member and frame.

We have taken advantage of these snap projections for effecting an engagement between the watch and the mounting member 10. This is accomplished by removing the frame 16 from the watch as by prying it therefrom as is conventional, tilting it as illustrated in Fig. 3, applying one snap projection in the bottom of the groove 13 through one side of opening 12, and pushing the other snap projection through the base of the smaller opening 11 until it is in radial alignment with groove 13. It will be understood therefore that the bottom of opening 11 by merging into opening 12 interrupts the continuity of opening 12 so as to provide an entrance for the frame snap projection into the groove 13. The frame 16 may then be rotated 90 degrees so that the projections are disposed transversely of the mounting member as illustrated in Figs. 1 and 2. At this time, the case body member 15, including the works, and the crown 19 are pushed through the other side of the opening 12 until its snap projections 17 are engaged by the projections 18 of the frame. This completes the engagement of the watch with the mounting member simultaneously with re-assembly of the watch and the combination will then appear as illustrated in Fig. 1. It will be observed that the diameter of the watch case is approximately equal to that of the larger opening 12 so that the projections in the groove secure the elements against disengagement.

The smaller opening 11 renders the crown manually accessible so that the watch may be wound without removing it from its mounting member. Opening 11 further provides an initial site where the frame snap projection may be introduced into the groove 13. Removal of the watch from its mounting is effected by prying the body member 15, including the works, away from the frame 16 so as to remove it from the mounting member. The frame 16 is then rotated 90 degrees in order to

bring one of the snap projections 18 into registry with the discontinuous portions of the openings or of the groove. The frame may then be tilted outwardly since one snap projection is no longer retained by the groove and the frame may thus be removed from opening 12.

A metal band 20 which may be of gold or any other desired metal embraces the mounting member 10 and may terminate in a loop 21 which permits the ensemble to be suspended as when the article is used as a pendant watch.

After the watch has been installed or applied to the mounting member as hereinabove described, it cannot rotate to a position where it can drop out and become lost because the crown of the works is restrained against such action by the walls of opening 11. Accordingly, the article can only be disassembled by removing the back or body member, including the works, therefrom in the manner above set forth and then rotating the frame to release either one of the projections as described, or both of them, if the larger opening 12 is made further discontinuous in an opposite or bottom portion thereof. This represents insurance against accidental loss, an advantage which is most important in these devices and which is achieved herein, notwithstanding the marked simplicity of assembly of the watch to the mounting member.

The mounting may be employed in many environments as in pendants, bracelets, brooches or any other form in which watches may be worn.

What is claimed is:

1. The combination of a watch and mounting therefor comprising a mounting member, said mounting member being formed with a circular opening therethrough and an arcuate groove formed in the wall of said opening and concentric therewith, said watch including at least one projection formed externally thereof, said projection being disposed in said groove so as to effect an engagement of said watch with said mounting member, said projection being rotatable in said groove in a path concentric with said opening.

2. The combination of a watch and mounting therefor comprising a mounting member, said mounting member being formed with a circular opening therethrough and a groove formed in the wall of said opening, said watch including at least one projection formed externally thereof, said projection being disposed in said groove so as to effect an engagement of said watch with said mounting member, said groove extending around the wall of said circular opening so as to be concentric with said circular opening.

3. The combination of a watch including a watch case and mounting therefor comprising a mounting member, said mounting member being formed with a circular opening therethrough and a circular groove formed in the wall of said opening and concentric therewith, said watch case including a pair of diametrically opposite externally formed projections, said projections being disposed in said groove and being engaged thereby so as to retain said watch case within said cir-

cular opening, said watch case comprising a body member and a frame held together by said projections.

4. The combination of a watch including a watch case and mounting therefor, said combination comprising a mounting member, said mounting member being formed with a circular opening therethrough and a circular groove formed in the wall of said opening and concentric therewith, said watch case including a pair of diametrically opposite externally formed projections, said projections being disposed in said groove and being engaged thereby so as to retain said watch case within said circular opening, and a second opening merging into said circular opening, said second opening providing an entrance for one of said projections into said groove.

5. The combination according to claim 4 and wherein said mounting member comprises a stone, and a metal band embracing said stone, said metal band being formed with an upwardly disposed loop for suspending the mounting member.

6. The combination of a watch having a case and a winding crown, and a mounting for said watch, said combination comprising a mounting member, said mounting member being formed with a circular opening therethrough and a peripheral groove formed in the wall of said opening and concentric therewith, said watch case including a pair of oppositely disposed projections formed externally thereof, said projections being disposed in said groove so as to effect an engagement of said watch with said mounting member, and a second opening formed above said circular opening and merging therewith, said watch case having an outside diameter approximately equal to the diameter of said circular opening whereby one of said projections may be initially placed in said smaller opening preparatory to entrance into said groove for effecting said engagement, said smaller opening being adapted to surround said crown of said watch.

7. A new article of manufacture comprising a mounting member for a watch, said mounting member being formed with a circular opening therethrough and a peripheral groove formed in the wall of said opening and concentric therewith, a second opening disposed laterally of said circular opening and merging therein so as to interrupt the circular continuity thereof and of the groove.
